(57) **CLAIM**

The ornamental design for a camera module, as shown and described.

DESCRIPTION

FIG. 1 is a front-left-top perspective view of a camera module showing the new design illustrated in a first orientation;

FIG. 2 is a rear-right-bottom perspective view thereof;

FIG. 3 is a top plan view thereof;

FIG. 4 is a bottom plan view thereof;

FIG. 5 is left side elevational view thereof;

FIG. 6 is a right side elevational view thereof;

FIG. 7 is a front side elevational view thereof; and

FIG. 8 is a rear side elevational view thereof.

FIG. 9 is a front-left-top perspective view of the camera module illustrated in a second orientation;

FIG. 10 is a rear-right-bottom perspective view thereof;

FIG. 11 is a top plan view thereof;

FIG. 12 is a bottom plan view thereof;

FIG. 13 is a left side elevational view thereof;

FIG. 14 is a right side elevational view thereof;

FIG. 15 is a front side elevational view thereof; and,

FIG. 16 is a rear side elevational view thereof.

The broken lines in the figures depict portions of the camera module in which the design is embodied that form no part of the claimed design.
